UNITED STATES PATENT OFFICE.

LOUIS A. CASGRAIN, OF BEVERLY, MASSACHUSETTS, ASSIGNOR TO UNITED SHOE MACHINERY CORPORATION, OF PATERSON, NEW JERSEY, A CORPORATION OF NEW JERSEY.

HEEL-BREASTING MACHINE.

Application filed April 17, 1919, Serial No. 290,670. Renewed October 23, 1922. Serial No. 596,464.

To all whom it may concern:

Be it known that I, Louis A. Casgrain, a citizen of the United States, residing at Beverly, in the county of Essex and State 5 of Massachusetts, have invented certain Improvements in Heel-Breasting Machines, of which the following description, in connection with the accompanying drawings, is a specification, like reference characters on 10 the drawings indicating like parts in the several figures.

This invention relates to machines for operating upon the breast portions of shoe heels and particularly to machines for forming 15 the breast portions of Louis heels after they are attached to their shoes.

Some shoe heels, for example, Louis heels, have their breast faces curved longitudinally of the shoe and are usually breasted by relatively moving the heels and the breasting 20 means transversely of the heels. When a heel is breasted by relative traversing movement of the heel and cutter or cutters transversely of the heel it is difficult to form a good edge 25 on the side of the heel where the cut is finished. It has been proposed to employ two cutters which cut from opposite sides of the heel and meet at the center of the breast. This method has been found impracticable because a fin or blemish will be 30 formed at the center of the breast. One object of this invention is to provide a machine employing cutters acting inwardly from opposite sides of the heel so organized and operated that not only will both 35 side edges of the heel breast be properly formed, but also so that no fin or blemish will be made on the breast face.

Heels of the Louis type have a portion adjacent to the heel-seat which extends forwardly of the shoe along the shank. The breast face of this portion should be formed, at its front edge, flush with the shoe shank and should be transversely curved to correspond with the transverse curve of the shank and to merge into the portion of the breast which extends heightwise of the heel. A further object of this invention is to provide 45 a machine having a contoured cutting blade so movable transversely of the heel as to cause the portion of the knife which

cuts the base portion of the heel breast to follow the transverse curve of the shank.

The portion of a heel breast adjacent to the top lift is frequently formed with a 55 curvature differing from that of the main portion of the breast. This curvature is generally concave relatively to the heel and is known as a scallop and is best formed by a rotary cutter having a predetermined 60 movement relatively to the heel of the shoe. A further object of this invention is to provide a machine having such a cutter and preferably with means for causing the cutter automatically to scallop the heel. 65

Other objects of the invention are to provide an improved machine for this work which will be more accurate, effective, and expeditious, and which will require less attention from an operator than prior machines. 70

A feature of the invention consists in an organization including work holding means and a pair of opposed cutters together with means for relatively moving 75 the work and one cutter to initiate the cutting operation at one side of the work, and means for relatively moving the work and the other cutter to complete the cutting operation. Preferably, the cutting operation 80 of the first cutter ceases prior to the completion of the action of the second cutter. As shown herein, the cutters begin to act at opposite sides of a face of the work and the surface formed by one cutter extends 85 to and preferably partly across the surface formed by the other cutter without any line of demarcation being formed between these surfaces. The invention is shown herein as embodied in a machine for breasting heels 90 and the two cutters are knives which operate from the sides of the heel toward its center. As shown the knives do not meet in the center of the heel but before the knives reach the center the action of one knife is arrested and, preferably, that knife is retracted while the action of the other knife continues past the center of the heel 95 completely to sever the chip.

Another feature of the invention consists in an organization in which a knife is moved in a curved or arcuate path transversely of

the shoe to treat the shoe bottom, for instance, to form a convex surface on a heel breast. In order convexly to curve a portion of the shoe bottom extending lengthwise of the shoe, for example the base portion of a Louis heel, the knife may be moved about an axis extending longitudinally of the shoe and preferably located substantially at the center of the curve of the shank so that the portion of the knife adjacent to the shank of the shoe will begin to cut substantially in the plane of the surface of the shank at its edge and will follow the curve of the shank as it advances toward the center of the heel breast, thereby cutting the front edge of the base portion of the heel flush with the surface of the shank and giving the remainder of the base portion a convexly curved surface corresponding to the curve of the shank. Preferably two knives are organized to act as described and are moved about a common axis. As shown, the knives may be contoured to form on the base portion of the heel a surface curved longitudinally of the heel and extending forwardly along the shank, the forward edge of the said portion being flush with the shank surface and following the transverse curve of the shank by reason of the movement of the knife about the said axis.

A further feature of the invention consists in an organization for relatively moving the knives and the heel bodily in the direction of the length of the heel and for operating the knives a second time in the cycle of the machine to cause the knives to make a second or finishing cut by which a thin chip is removed from the heel by a movement of the knives which is parallel to the first movement. As shown, the knives are moved bodily rearwardly of the heel between successive operations of the knives.

Another feature of the invention consists in an organization comprising means for holding the shoe in a fixed position, means for breasting the heel, and a rotary cutter for giving a portion of the breast face a shape different from that formed by the breasting means. As shown herein, the rotary cutter forms a concavity or scallop on the portion of the breast face adjacent to the top lift of the heel. Preferably the rotary cutter is arranged for movement substantially lengthwise of the heel about an axis above the cutter and over the rear part of the shoe so that the cutter may be swung into operative relation to the heel breast, the path of swinging movement being such as to include a slight component of movement heightwise of the heel toward the shoe so as to cause the cutter to move into position opposite to the portion of the heel breast which is adjacent to the toplift before it

is moved further lengthwise of the heel to perform its cutting operation. The cutter is preferably frusto-conical in shape and arranged with its shorter diameter at the greater distance from the shoe. In the organization shown, the cutter is continuously rotated and is swung in timed relation to the action of the breasting means to move it from a position where it is out of the path of the shoe when inserted into the machine into operative relation to the heel and then back to its initial position where it is out of the way of the shoe during the removal of the shoe, the movements of the cutter being effected automatically.

Since the knives and the rotary cutter are moved in predetermined paths to do their work, it is important that the shoe be held in the machine in a predetermined position. Accordingly, a still further feature of the invention consists in an organization comprising stops movable into and out of position over the shoe bottom and means for clamping the shoe against the stops. As shown, the stops are located one at each side of the shoe and are movable from positions laterally beyond the shoe to positions over the marginal portions of the shoe shank adjacent to the breast of the heel. Preferably movement of the stops over the shoe shank is effected manually, for example, by a treadle, and further movement of the same treadle may conveniently be utilized to set the machine in operation.

Another feature of the invention consists in an organization including a stop or abutment and means for clamping the shoe against the stop comprising means engaging and supporting the cone of the last which is compressible by pressure on the shoe to allow lasts of various heights to be readily positioned in the machine, with means for locking the supporting means from depression and applying thereto a predetermined movement toward the stop to ensure that a last of any height will be firmly seated against the stop before the shoe is operated upon. The locking of the shoe support and the predetermined clamping movement are, as shown herein, effected by power operation of the machine. Preferably two stops are provided as above explained.

Other features of the invention consist in improved means for locating the heel and toe of the shoe and in other details of construction and combinations of parts which, as well as the features above mentioned, will appear more fully from the following detailed description when read in connection with the accompanying drawing and will be pointed out in the appended claims.

In the drawing,

Fig. 1 is a side elevation of a machine embodying this invention, part of the base portion of the frame being broken away;

Fig. 1^a is a sectional detail taken on the line 1^a—1^a of Fig. 1;

Fig. 2 is a front elevation of the machine, the front portion of the base being broken 5 away;

Fig. 2^a is a sectional detail taken on the line 2^a—2^a of Fig. 2;

Fig. 3 is a plan view of mechanism located 10 at the top of the machine;

Fig. 4 is a plan view, partly in section, of the means for mounting and operating the knives; and

Fig. 5 is a sectional detail taken on the line 5—5 of Fig. 1.

In the drawings, the numeral 2 indicates 15 the frame of the machine, in the lower part of which is mounted a shaft 4 to which are secured various cams to be referred to hereinafter by which certain instrumentalities 20 with which the machine is provided are operated. A driving pulley 6 is loosely mounted on the rear end of the shaft 4 and is continuously driven by belt connection to a suitable source of power. Means is provided 25 between the pulley and the shaft 4 for imparting to the shaft a single revolution at each depression of a treadle 8. This means may comprise a one-revolution clutch of any suitable type.

To support the shoe in the machine a jack 30 is provided which has a last pin 10 adapted to enter the pin hole of the last. The pin 10 is mounted on a block 12 which is pivoted at 14 to the upper end of a jack post 16.

To hold the block 12 from movement about 35 the pivot 14 and to enable the angular relation of the pin 10 to the post 16 to be varied, a part 18 is clamped to the post and a screw 20 is threaded through the part 18 and engages the block 12. By turning the screw 20 the block 12 may be tipped about the pivot 14. The post 16 is arranged to slide longitudinally in a sleeve member 22 and is normally held in raised position by a spring 24 40 (Fig. 2^a) which engages the post 16 at one end and rests upon a screw plug 26 inserted in the member 22 at the other end. The member 22 is pivoted at 28 for swinging movement to permit a shoe to be moved longitudinally into and out of the machine, and to limit its swinging movement the member 22 is provided with lugs 30, 32 which are arranged to engage respectively the upper and lower faces of a lever arm 34 to which the member 22 is pivoted at 28. A shoe is placed 45 upon the pin 10 of the jack with the jack in outwardly swung position and is then moved longitudinally toward the machine. the heel passing between stop arms 40, 42 which at that time are separated to permit passage of the heel between them. During this movement the post 16 is depressed somewhat against the spring 24 to permit the tread face 50 of the heel to pass beneath a tread plate 46 mounted for adjustment longitudinally of the shoe upon the forward end of a lever 48 pivoted to the machine frame at 50. The plate 46 has a flange 52 which engages the rear end of the heel and limits rearward movement thereof. Passing through the lever 48 is a rod 54 having below the lever a collar 56 which limits downward movement of the lever and above the lever having a spring 58 which normally holds the lever 48 against the collar 56. After the shoe has 55 been positioned beneath the tread plate 46 it is released by the operator and raised by the spring 24 into contact with the plate 46, the spring 58 being somewhat stiffer than the spring 24 so as to maintain the spring 24 60 under tension and the lever 48 against the collar 56. The adjustment of the collar is such that the plane of the shoe shank will be below the plane of inwardly swinging movement of the stop arms 40, 42. These arms 65 are pivoted at 60, 62, respectively, to the transverse portion 64 of a U-shaped member, the arms 66, 68 of which are pivoted at 70 to the machine frame. The arms 66, 68 are slotted as at 72 (Fig. 1) and cap screws 73 75 pass through the slots and are threaded into the machine frame. By loosening the screws 73 the U-shaped member may be swung about the pivot 70 and hence the stop members 40, 42 adjusted vertically for a purpose which 80 will appear hereinafter. Above their pivots 60, 62 the stop members 40, 42 are provided with extensions 80, 82 (Fig. 2) which are acted upon by a wedge member 84 mounted in 85 guides in the frame and operated by a lever 86 pivoted at 88 to the frame and connected at its rear end to a rod 90, the lower end of which is guided in the frame and rests upon a lever 92 which is pivoted to the frame at 94 and its forward end formed as the treadle 8. The lever 92 extends rearwardly beyond the rod 90 and has connections to the clutch so that depression of the treadle 8 will first raise the rod 90 and thereafter trip the clutch. Raising of the rod 90 causes depression of the wedge member 84 which causes the stop members 40, 42 to approach each other and assume positions over the shank of the shoe. The wedge member 84 has parallel edge faces 90 which engage the projections 80, 82 after the wedge portion has effected the desired movement of the stop members 40, 42 and hence movement of the wedge member 84 may be continued by further depression of the treadle to trip the clutch. The position of the shoe shank as determined by the tread plate 46 will, of course, vary with heels of different heights and, therefore, the collar 56 should be so adjusted that the shank of the shoe being operated upon will be located in a 95 plane somewhat below the plane of swinging movement of the stop members 40, 42.

After the shoe has been positioned as described, the treadle will be partially depressed to move the stop members 40, 42 over 100

105

110

115

120

125

130

the shoe shank and thereafter further depressed to start the machine. In the drawings, the machine is shown as having started and the shaft 4 as having moved through about 30° of its rotation. In order to hold the shoe firmly in predetermined position, it is important to press the shoe firmly against the stop members 40, 42. In the construction shown this is effected by first locking the post 16 against depression and then lifting the member 22 to force the shoe against the stop members. The post 16 is provided on its rear face with teeth 100 (Fig. 2a) which are engaged by a pawl block 102 which is urged into locking engagement with the teeth 100 by a leaf spring 104 and is mounted on an arm 106 of a rock shaft 108 mounted in a rearward projection of the sleeve member 22. Another arm 110 of the rock shaft 108 is connected by a link 112 to the forward end of a lever 114 pivoted to the lever 34 at 116 and connected between its ends to the machine frame by a link 118. The lever 34 is pivoted to the machine frame at 120 and its rearwardly extending arm 35 is pivoted at 121 to a rod 122 connected at its lower end to an arm 124 of a bell crank lever fulcrumed on a shaft 126, the other arm 128 of the bell crank carrying a roll 130 which engages an edge cam 132 mounted on the shaft 4. Before the machine starts the pawl block 102 is out of engagement with the teeth 100, and when the machine starts the cam 132 moves the arm 128 to the right (Fig. 2) effecting a downward pull on the rod 122 and causing the outer end of the lever 34 to be raised, carrying with it the sleeve member 22. Since the outer end of the arm 110 is held by the connections 112, 114, 118 from substantial movement with the sleeve member 22, the pawl block 102 is caused to engage the teeth 100, further predetermined movement of the lever 34 causing the shoe to be positively raised and forcibly clamped against the stop members 40, 42. The tread plate 46 is raised, of course, by the shoe and the spring 58 somewhat compressed. In order, however, firmly to hold the heel it is desirable to increase the tension of the spring 58 when the shoe is jacked and this is accomplished by connecting the rod 54 to the lever arm 35 at 121 so that as the arm 35 is depressed as described the rod 54 will be pulled down and increased tension applied to the spring 58.

It will be observed that by the mechanism described shoes having lasts of different heights are positioned and raised upwardly with substantially the same predetermined pressure against the stops 40, 42. The last and shoe are first measured by insertion between the tread plate 46 and the yielding jack post 16. Then the jack post is locked by the pawl 102 in the position it has been made to assume by the height of the partic-

ular last and the post raised by the positive movement of the lever 34 to force the shoe against the stops 40, 42.

In order to position the shoe more accurately and to prevent the downward pressure of the tread plate 46 from tipping the forepart of the shoe upwardly, a rest 136 is provided which has a stem 138 adjustably held in a split clamp 140 mounted on the outer end of a rod 142 which is adjustably secured in the machine frame by a set screw 144. The wedge member 84 is slotted to permit the passage of the rod 142 through it and to permit movement of the wedge member as described.

The shoe is now positioned and held for the operation of the breasting knives 150, 152 which are located one on each side of the heel and are moved transversely of the heel breast toward the center of the heel. As shown in Fig. 2, the knives 150, 152 are segment-shaped or, strictly, are shaped as sectors of an annulus, and are mounted to oscillate about an axis 154 which extends longitudinally of the shoe and is located substantially at the center of transverse curvature of the shoe shank. Preferably the knives are contoured as shown in Fig. 4 so that the portions of the knives adjacent to the base of the heel will form upon the heel a forwardly projecting portion which is convex relatively to the shank, the front edge portion of which is trimmed flush with the surface of the shank. The knife 150 is clamped to an arm 156 as shown in Fig. 4. One edge of the knife rests against a flange 158 and the other edge of the knife is engaged by a clamping piece 160 which has a bearing at 162 in the arm 156 and is forced against the knife edge by a screw 164. The arm 156 is mounted on the bearing shaft 154 and extends to the left hand side of the machine where it is connected by a bolt 166 to a rod 168 which is connected at its lower end to a lever 170 (Fig. 2) fulcrumed on the shaft 126 and having thereon a cam roll 172 which engages a suitable cam path formed in a cam block 174 affixed to the shaft 4 (Fig. 1.) The knife 152 is mounted on an arm 176 by means similar to that described for clamping the knife 150, and the arm 176 has a sleeve 178 which surrounds the shaft 154 and hence permits movement of the knife 152 about the same axis as the knife 150. The arm 176 extends to the right hand side of the machine where it is connected by a bolt 180 to a rod 182 which is connected at its lower end to a lever 184 fulcrumed on a shaft 186 and having between its ends a cam roll 188 which engages a suitable cam path formed in the front face of the cam block 174. The arm 156 is shaped, as shown in Fig. 2, to pass beneath the arm 176 and avoid interference therewith when the rods 168, 182 are drawn downwardly by their respective

125. 130.

cams to cause the knives to be oscillated about the axis 154 and their edges advanced toward the center of the heel. The portions of the knives next to the shank, by virtue of the location of the axis 154 at the center of the curve of the shank, follow the transverse curve of the shank and form the base portion of the heel in conformity thereto.

In order to form a smooth breast face on the heel it is desirable to perform the breast-
10 ing operation in two steps, first by removing a thick or roughing chip, and then by the removal of a thin or finishing chip. In the construction herein shown the first or
15 roughing chip is cut as described but the action of the knives is arrested before they meet at the center of the heel and the knives are then withdrawn, the roughing chip remaining attached to the heel breast. The
20 knives are then moved bodily rearwardly of the heel a short distance and are again operated toward the center of the heel. The bodily rearward movement of the knives is effected by the following mechanism: Out-
25 side of the sleeve 178 is another sleeve 190 and both the shaft 154 and the sleeve 178 are held from longitudinal movement in the sleeve 190 by a washer 192 secured by a nut 194, as shown in Fig. 4. The sleeve 190 is
30 provided with a slot 196 (Figs. 1 and 1^a) which is inclined to the direction of the axis 154 and which is engaged by a screw stud 198 threaded through the machine frame and having a frusto-conical end which enters the slot 196. The sleeve 190 is provided
35 with an arm 200 connected by a bolt 202 to a rod 204, the lower end of which is pivoted at 205 to a lever 206 fulcrumed on the shaft 186 and having between its ends a cam roll
40 which engages a cam path in the rear face of a cam block 208. After the knives are operated partially to remove the roughing chip and withdrawn the cam 208 acts through the rod 204 to pull down on the arm 200, thereby rocking the sleeve 190 and causing it, by reason of the engagement of the fixed stud 198 with the slot 196, to be moved rearwardly, carrying with it the bearings 154, 178 of both the knives. This
45 rearward movement, of course, is very slight, a movement of one thirty-second of an inch being usually sufficient. The knives are again operated to approach the center of the heel and to remove a finishing chip from the portion already roughly breasted. It is, of course, impracticable to move the knives until they meet in the center of the heel, one reason being that if the knives
50 are adjusted so that they will practically meet when no shoe is being breasted they would fail to meet when under the stress of performing the breasting operation by reason of springing of the parts, and as a result a fin or rough place would be formed at the

center of the heel breast. To avoid this difficulty among others, in the construction shown the knives, upon their second cut, are made to approach each other as on the first cut, and then the action of one knife is arrested and the knife preferably withdrawn while the action of the other knife continues slightly past the center of the heel and effects a complete and clean severance of that chip as well as of the first chip which clings to it. This action of the knives is effected, of course, by suitably shaping the cam paths which operate the knives, as will be readily understood.

After the breast face of the heel has been formed in the manner described, it is usually desirable to form a concaved portion on the breast face of the heel adjacent to the top lift, usually referred to as a scallop. In the machine herein shown this operation is effected automatically by the following mechanism: A rotary cutter 210 is mounted on a shaft 212 on the opposite end of which is a pulley 214 which is continuously driven by a belt 216 extending over idler pulleys 218 to a pulley 219 on a counter shaft 220. A pulley 222 on the counter shaft and fast with the pulley 219 is belted to a portion 224 of the driving pulley 6. The shaft 212 of the rotary cutter is mounted in a carrier 226 which is pivoted to the machine frame at 228 on an axis extending transversely of the shoe and has a rearwardly extending arm 230 to which is connected at 232 a rod 234. The lower end of the rod 234 is connected at 236 to a lever 238 fulcrumed on the shaft 126 and having thereon a cam roll 240 (Fig. 1) which engages an edge cam formed on the cam block 208. After the breasting of the heel has been effected as described, the roll 240 is actuated to push upwardly on the rod 234 lifting the arm 230 and causing the cutter shaft to move about the axis 228 and the cutter to approach the breast face of the heel and perform thereon the scalloping operation. Since the cutter shaft 212 is inclined to the direction of the height of the heel, and its carrier moves about the axis 228 which is located rearwardly of the heel, the cutter not only moves lengthwise of the heel into operative relation to the heel, but has a component of movement heightwise of the heel so that it descends from a location above the plane of the toplift to a position slightly below that plane prior to the continued lengthwise movement which causes it to engage and scallop the heel. Preferably the cutter 210 is provided with a shield 242 which extends around all portions of the cutter except the portion which acts upon the heel. It will be noted that the stop members 40, 42 are shaped to accommodate between them the rotary cutter and its shield.

Having thus described my invention,

what I claim as new and desire to secure by Letters Patent of the United States is:

1. In a machine of the class described, the combination of means for holding the work, a plurality of non-rotary knives, means for moving the knives in opposite directions partially to sever a chip from the work, and means for moving the knives in the same direction to complete the severance 10 of the chip.
2. In a machine of the class described, the combination of means for holding the work, a plurality of non-rotary knives, means for effecting relative movement of the knives partially to sever a chip from the work, and means for moving both knives and the work relatively to complete the severance of the chip.
3. In a machine of the class described, the combination of means for holding the work, a plurality of non-rotary knives, means for moving the knives in opposite directions partially to sever a chip from the work, and means for moving one knife 20 farther than the other knife is moved completely to sever the chip.
4. In a machine of the class described, the combination of means for holding the work, a plurality of non-rotary knives, and means for moving the knives first in opposite directions and then in the same direction to sever the chip from the work.
5. In a machine of the class described, the combination of means for holding the work, a plurality of non-rotary knives, means for moving the knives relatively partially to sever the chip, and means for further operating the knives to effect complete 30 severance of the chip.
6. In a machine of the class described, the combination of means for holding a shoe heel, a plurality of cutters, means for relatively moving the heel and one cutter to effect a cutting operation at one side of the heel, and means for reversely relatively moving the heel and the other cutter to complete the cutting operation.
7. In a machine of the class described, the combination of means for holding a shoe 40 having a heel attached thereto, a plurality of knives, means for moving the knives relatively partially to sever a chip from the breast of the heel, and means for further and differently operating the knives to effect complete severance of the chip.
8. In a machine of the class described, the combination of means for holding a shoe having a heel attached thereto, a plurality of cutters, means for relatively moving the shoe and one cutter to effect a cutting operation from one side of the heel, and means for then relatively moving the heel and the other cutter to complete the cutting operation.
9. In a machine of the class described,
- the combination of a shoe support, a plurality of knives arranged to move from the sides of the heel toward the center, means to cause one knife to stop before reaching the center and to retract, and means for causing the other knife to move past the center to sever the chip before retraction.
10. In a machine of the class described, the combination of means for holding the work, a plurality of knives arranged to oscillate about a common center, means for moving the knives in opposite directions about said center partially to sever the chip from the work, and means for moving the knives in the same direction to complete the severance of the chip.
11. In a machine of the class described, the combination of means for holding the work, a plurality of knives constructed and arranged to move in a curved path across a single face of the work, means for effecting relative movement of the knives partially to sever the chip from the work, and means for moving both knives and the work relatively to complete the severance of the chip.
12. In a machine of the class described, the combination of means for holding the work, a pair of knives, means for moving the knives in circular arcs in opposite directions transversely of the work partially to sever the chip from the work, and means for moving one knife farther than the other knife is moved completely to sever the chip.
13. In a machine of the class described, the combination of means for holding the work in fixed position, a plurality of knives, and means for moving the knives about an axis first in opposite directions to form an unsevered chip and then in the same direction to sever the chip from the work.
14. In a machine of the class described, the combination of a shoe support, a plurality of knives constructed and arranged to move from side to side of the heel and to follow the convex face of the shoe shank, and means for relatively operating the shoe support and knives to effect their operation on the shoe.
15. In a machine of the class described, the combination of a shoe support, and a plurality of knives arranged to approach each other from opposite sides of the heel to breast the heel, said knives being constructed and arranged to follow the convex face of the shoe shank.
16. In a machine of the class described, the combination of a heel support, and a plurality of knives arranged to oscillate about a center located below the seat face of the heel on the support.
17. In a machine of the class described, the combination of a shoe support constructed and arranged to hold a shoe and its attached heel in a predetermined position, a plurality of knives constructed and ar-

ranged to form a flat face on the portion of the heel breast adjacent to the top lift, and means for relatively operating the shoe support and knives to cause the knives to follow the curve of the shank.

18. In a machine of the class described, the combination of a shoe support, and a pair of knives arranged to approach each other from opposite sides of the heel, said knives being constructed and arranged to form a flat face on the portion of the heel breast adjacent to the top lift and to follow the curve of the shoe shank.

19. In a machine of the class described, the combination of a shoe support, and a plurality of knives arranged to oscillate about a center located at the center of the curve of the shoe shank.

20. In a machine of the class described, the combination of a shoe support, and a plurality of knives arranged to oscillate about a common center located in the longitudinal median plane of the shoe on the support and below the surface of its shank.

21. In a machine of the class described, the combination of a shoe support, and a plurality of knives arranged to move from a position beyond the sides of the heel toward its center in circular arcs.

22. In a machine of the class described, the combination of a shoe support, a plurality of knives arranged to move from the sides of the heel toward the center, and means for causing the knife edges to move in the direction of the height of the heel during their approaching movement to cause the portions of the knives next to the shank to follow the curve of the shank.

23. In a machine of the class described, the combination of a shoe support, a knife blade, a carrier therefor movable transversely of the heel about an axis located at the center of the curve of the shank, and means for operating the carrier to cause the portion of the blade adjacent to the shank to follow the curve of the shank during its transverse movement.

24. In a machine of the class described, the combination of means for holding the work, a plurality of knives, means for effecting relative movement of the knives partially to sever a chip from the work, means for moving relatively the work and the knives, and means for operating the knives a second time to remove another chip from the work and completely to sever both chips from the work.

25. In a machine of the class described, the combination of means for holding the work, a plurality of knives, means for moving the knives in opposite directions partially to sever a chip from the work, means for moving relatively the work and the knives, means for again operating the knives partially to sever a second chip from the work,

and means for moving one knife farther than the other knife to complete the severance of both chips.

26. In a machine of the class described, the combination of means for holding the work, a plurality of knives, means for causing the knives to approach each other partially to sever a chip from the work and withdraw, means for relatively moving the work and the knives, means for causing the knives again to approach each other partially to sever a second chip from the work, and means for moving the knives in the same direction completely to sever the second chip.

27. In a machine of the class described, the combination of means for holding a shoe, a plurality of knives, means for effecting relative movement of the knives partially to sever a chip from the breast of the shoe heel, means for moving relatively the shoe and the knives lengthwise of the shoe, and means for operating the knives a second time to remove another chip from the work and completely to sever both chips from the work.

28. In a machine of the class described, the combination of means for holding the work, a plurality of knives, means for moving the knives in opposite directions partially to sever a chip from the work, means for moving relatively the work and the knives, means for again operating the knives partially to sever a second chip from the work, and means for withdrawing one knife and moving the other knife farther to complete the severance of both chips.

29. In a machine of the class described, the combination of means for holding a shoe heel, a pair of knives, means for causing the knives to approach each other partially to sever a chip from the heel and withdraw, means for relatively moving the heel and the knives lengthwise of the heel, means for causing the knives again to approach each other partially to sever a second chip from the heel, and means for moving both knives in the same direction completely to sever the second chip.

30. In a machine of the class described, means for holding a heel, a pair of knives movable from the sides of the heel toward the center of its breast, means for moving the knives until they nearly meet at the center of the breast partially to sever a roughing chip and for withdrawing the knives, means for moving the knives bodily rearwardly of the heel, and means for again operating the knives to remove a finishing chip completely from the heel breast.

31. In a machine of the class described, means for holding a heel, a pair of knives movable from the sides of the heel toward the center of its breast, means for moving the knives until they nearly meet at the

- center of the breast partially to sever a roughing chip and for withdrawing the knives, means for moving the knives bodily rearwardly of the heel, means for again operating the knives partially to sever a finishing chip from the heel breast, and means for withdrawing one knife and giving further movement to the other knife completely to sever the finishing chip. 5
- 10 32. A machine of the class described having, in combination, heel breasting means, rotary heel breast scalloping means, and means for effecting automatically first relative movement of the shoe and breasting means to cause the heel to be breasted and then relative movement of the rotary means and shoe to cause the heel breast to be scalloped. 70
- 15 33. A machine of the class described having, in combination, heel breasting means, a rotary heel breast scalloping cutter, a shoe support, and means for effecting automatically relative movements of the shoe support, the breasting means and the scalloping means to cause the breasting means and the scalloping means to operate successively upon the heel breast. 75
- 20 34. In a machine of the class described, the combination of an intermittently operated breasting knife, a continuously operated cutter, and means for causing the knife and the cutter to operate upon the heel breast in succession. 80
- 25 35. In a machine of the class described, the combination of an intermittently operated breasting knife, a continuously operated cutter, and automatic means for causing the knife first to breast the heel and then causing the rotary cutter to scallop the heel breast. 85
- 30 36. In a machine of the class described, the combination of means for holding the shoe in predetermined position, a rotary cutter, a support therefor arranged to swing about an axis above the heel, and means for swinging the cutter into operative relation to the heel breast to effect a scalloping operation thereon. 90
- 35 37. In a machine of the class described, the combination of means for holding the shoe in predetermined position, a rotary cutter, a support for the cutter arranged for movement about an axis extending transversely of the shoe above its heel, and means for moving the support about said axis to bring the cutter into operative relation to the heel breast to effect a scalloping operation thereon. 95
- 40 38. In a machine of the class described, knives arranged to breast a heel by movement transversely of the heel breast, shoe supporting means, means for relatively moving the knives and supporting means to effect a breasting operation, a rotary cutter constructed and arranged to form a concave face on the breast portion of the heel adjacent to the top lift, and means for relatively moving the shoe supporting means and the cutter to cause the rotary cutter to do its work. 100
- 45 39. In a machine of the class described, the combination of a shoe support, and a knife movable bodily transversely of the heel and contoured to form on the heel a portion curved longitudinally of the heel and extending forwardly of the shoe, said knife being constructed and operated to cause the portion of the knife adjacent to the shank to follow the curve of the shank during transverse bodily movement of the knife. 105
- 50 40. In a machine of the class described, knives arranged to breast a heel by movement transversely of the heel breast, shoe supporting means, means for relatively moving the knives and supporting means to effect a breasting operation, a rotary cutter, and means acting automatically after the breasting operation for moving the cutter to cause the cutter to form a concave face on the breast portion of the heel adjacent to the top lift. 110
- 55 41. In a machine of the class described, the combination of means for holding the shoe in predetermined position, heel breasting means, a rotary cutter normally above the heel, and means for bringing the cutter into operative relation to the heel breast to effect a scalloping operation thereon. 115
- 60 42. In a machine of the class described, the combination of stops movable laterally of the shoe from a position laterally beyond the shoe at each side of the shoe to positions over the shoe shank, means for relatively moving the shoe and said stops to hold the shoe against them, and means for breasting the heel while so held. 120
- 65 43. In a machine of the class described, the combination of stops movable laterally of the shoe from a position laterally beyond the shoe at each side of the shoe to positions over the shoe shank and having predetermined vertical positions, means for jacking the shoe against the stops, and breasting means acting to form the base of the heel to correspond to the transverse curve of the shank. 125
- 70 44. In a machine for breasting heels, the combination of stops movable in a plane parallel with the heel breast from a position laterally beyond the shoe to a position over the shoe shank, means for relatively moving the shoe and said stops to hold the shoe against the stops, and means for breasting the heel while so held. 130
- 75 45. In a machine of the class described, the combination of stops movable in a plane substantially perpendicular to the shoe bottom from a position laterally beyond the shoe to a position over the shoe shank and having a predetermined vertical position, means for jacking the shoe against the stops, 135

and breasting means having a cutting portion which acts in the plane of the shoe engaging faces of the stops.

46. In a machine of the class described, the combination of heel breasting means, stops arranged to be moved laterally of the shoe from a position where they are located at each side of the shoe, out of the way of longitudinal movement of the shoe to a position over the shoe bottom, means for clamping the shoe against the stops, and means for thereafter operating the breasting means.

47. In a machine of the class described, knives arranged to breast a heel by movement transversely of the heel breast, shoe supporting means, means for relatively moving the knives and supporting means to effect a breasting operation, a rotary cutter having an axis located in the longitudinal median plane of the shoe, a support for said cutter movable about an axis extending transversely of the shoe, and means for moving the cutter support about said transverse axis to cause the rotary cutter to form a concave face on the breast portion of the heel adjacent to the top lift.

48. In a machine of the class described, the combination of heel breasting means, a stop arranged for movement laterally of the shoe in a plane substantially perpendicular to the shoe bottom from a position where it is out of the way of longitudinal movement of the shoe to a position over the shoe bottom, means for clamping the shoe against the stop, and means for thereafter operating the breasting means.

49. In a machine of the class described, the combination of heel breasting means, a pair of stops arranged for movement laterally of the shoe from a position where they are out of the way of the shoe to a position over the shoe bottom, manually operated means for moving the stops, and means under the control of the manual means for effecting automatically the clamping of the shoe against the stops and then causing the breasting means to operate.

50. In a machine of the class described, the combination of a pair of stop members for engaging a shoe bottom, said stop members being fixed as to movement in the direction of the height of the heel and movable laterally of the shoe from positions where they are out of the way of movement of the shoe and heel longitudinally of the shoe to positions over the shoe bottom, means for holding the shoe against said stop members, and breasting means movable laterally of the shoe parallel to the shoe engaging faces of the stop members.

51. In a machine of the class described, the combination of a pair of stop members for engaging a shoe bottom, said stop members being fixed as to movement in the di-

rection of the height of the heel and movable laterally of the shoe to afford a free passage for introduction of the shoe between them by longitudinal movement of the shoe, means for moving the stop members over the shoe bottom, means for holding the shoe against said stop members, and breasting means movable laterally of the shoe parallel to the shoe engaging faces of the stop members.

52. In a machine of the class described, the combination of a pair of stop members for engaging a shoe bottom, said stop members being fixed as to movement in the direction of the height of the heel and normally positioned out of the way of introduction of the shoe by longitudinal movement of the shoe between them, a support for the shoe movable to introduce the shoe between the stop members, means for moving the stop members to positions over the shoe bottom, means for raising the shoe support to clamp the shoe against the stop members, and breasting means acting to form a surface on the heel parallel to the shoe engaging faces of the stop members.

53. In a machine of the class described, the combination of a pair of opposed non-rotary cutters, means for presenting work from which a portion is to be severed to the cutters, and means for moving one of the cutters toward the other to an extent to cause them partially to sever a portion of the work and for thereafter moving the cutters simultaneously both in the same direction to complete the severing operation.

54. In a machine of the class described, the combination of a shoe support, a pair of cutters, means for relatively moving the support and both cutters partially to breast the heel of a shoe, and means for relatively moving the support and one of the cutters to complete the breasting operation.

55. In a machine of the class described, the combination of means for holding the work in fixed position, a plurality of non-rotary cutters, means for effecting relative movement of the cutters partially to sever a portion from the work, and means for moving the cutters relatively to the work to complete the severance of said portion.

56. In a machine of the class described, the combination of means for holding the work, a plurality of non-rotary cutters, means for effecting relative movement of the cutters partially to sever a portion from the work, and means for moving relatively the cutters and the work without relative movement of the cutters to complete the severance of said portion.

57. In a machine of the class described, work holding means, a pair of opposed non-rotary cutters, means for relatively moving the work holding means and one cutter to initiate the cutting operation at one side of

- the work, and means for relatively moving the work holding means and the other cutter to complete the cutting operation.
58. In a machine of the class described, the combination of means for holding the work in fixed position, a plurality of reciprocating knives constructed and arranged to sever the work by a cutting movement of each knife, and means for moving the knives in opposite directions toward and from the work without meeting, one knife being moved in its cutting stroke farther than the other knife is moved to cut completely through the work.
59. In a machine of the class described, means for holding a shoe, and a plurality of non-rotary knives movable in arcuate paths transversely of the shoe bottom in directions from side to side of the shoe.
60. In a machine of the class described, means for holding a shoe in predetermined position, a non-rotary knife mounted at one side of the shoe for movement transversely of the shoe from one side of the shoe toward the other side in an arcuate path, and means independent of the shoe for operating the knife in said path.
61. In a machine of the class described, means for locating a shoe in predetermined position, a pair of non-rotary knives located one at each side of the shoe, and means for moving the knives in arcuate paths from each side toward the center to form on the shoe an outwardly convex surface.
62. In a heel breasting machine, means for locating a shoe in predetermined position, a pair of knives, and means for moving the knives bodily relatively to the shoe heel to form on the heel breast an outwardly convex surface.
63. In a machine of the class described, means for locating a shoe in predetermined position, a pair of non-rotary knives located one at each side of the shoe, each knife having cutting portions in different planes, and means for moving the knives in arcuate paths to form on each side of the shoe surfaces which are in different planes relative to each other, one surface formed by each knife being curved transversely of the shoe bottom.
64. In a machine of the class described, the combination of means for holding a shoe heel in predetermined position, a rotary tool arranged for movement relatively to the heel, and automatic means for moving the tool in predetermined relation to the heel to perform a scalloping operation on the heel breast.
65. A machine of the class described having, in combination, shoe positioning means, and a rotary cutter arranged for movement substantially lengthwise of the heel to cause it to engage the breast only of the heel to remove material therefrom.
66. A machine of the class described having, in combination, shoe positioning means, and a rotary cutter normally positioned over and above the shoe bottom and arranged for movement substantially lengthwise of the heel to cause it to engage the breast only of the heel to remove material therefrom.
67. In a machine of the class described, shoe supporting means, a rotary cutter constructed and arranged to form a concave face on the breast portion of the toplift of a heel, and means for moving the cutter relatively to the heel lengthwise and heightwise thereof to cause the cutter to do its work.
68. In a machine of the class described, the combination of means for holding a shoe heel in predetermined position, a rotary tool arranged for movement lengthwise of the heel, and means for moving the tool to treat the heel breast.
69. In a machine of the class described, the combination of means for holding a shoe heel in predetermined position, a rotary tool arranged for movement relatively to the heel, and power operated means for moving the tool bodily heightwise of the heel into operative position and lengthwise of the heel to treat the heel breast.
70. A machine of the class described having, in combination, shoe positioning means, and a rotary cutter located over and above the shoe bottom and arranged for movement substantially lengthwise of the heel with a component of movement heightwise of the heel to cause it to engage the heel breast.
71. In a machine of the class described, the combination of means for holding a heel in predetermined position, a rotary tool arranged for movement relatively to the heel, and automatic means for giving the tool a predetermined movement substantially lengthwise of the heel to perform an operation on the heel breast.
72. In a machine of the class described, the combination of heel breasting means, rotary heel scalloping means, means for operating the breasting means to breast the heel, and means for moving the scalloping means to scallop the heel breast.
73. In a machine of the class described, the combination of intermittently operated breasting means, continuously operated scalloping means, and automatic means for causing the breasting means and the scalloping means to operate upon the heel breast in succession.
74. In a machine of the class described, the combination of breasting means, rotary heel scalloping means, means for operating

the breasting means to breast the heel, and automatic means for operating the scalloping means to scallop the heel breast.

75. In a machine of the class described, 5 the combination of heel breasting means, rotary heel scalloping means, means for relatively moving the breasting means and the heel to effect the breasting operation, and means for moving the scalloping means relatively to the heel to effect the scalloping operation on the heel breast.

76. In a machine of the class described, means for operating on a shoe which requires location of the shoe at a predetermined height, a shoe support movable to carry the shoe toward and from position to be operated upon, means for raising the support, and means comprising positioning members located on opposite sides of the longitudinal median plane of the shoe fixed as to vertical movement and movable toward and from said plane to engage and locate the shoe at said predetermined height.

77. In a machine of the class described, 25 the combination of stops having fixed vertical positions arranged to engage opposite sides of the shoe shank adjacent to the heel breast, a shoe support movable to press the shoe against said stops, operating means arranged to operate on a shoe in a predetermined manner with relation to its position as determined by its relation to said stops, and means for separating the stops to permit passage of the shoe heel between them.

78. In a machine of the class described, 35 the combination of means for operating on a shoe bottom, normally separated stops located one at each side of the shoe, a shoe support movable relatively to the stops to carry the shoe by longitudinal movement between said stops and beneath the operating means, means for closing the stops over the shoe to limit movement of the shoe toward the operating means, and means for raising and holding the shoe against said stops.

79. In a machine of the class described, 50 the combination of means for operating on a shoe bottom, normally separated stops located one at each side of the shoe, a last support movable to carry the shoe between said stops beneath the operating means, means for closing the stops over the shoe to limit movement of the shoe toward the operating means, and means for effecting a predetermined positive movement of the last support to hold the shoe against said stops, said means being arranged to act uniformly irrespectively of the height of the last.

80. In a machine of the class described, 60 the combination of means for operating upon a shoe, a stop movable into and out of position over the shoe bottom, and manually operable means arranged first to position

said stop over the shoe bottom and then to start the operating means.

81. In a machine of the class described, 65 the combination of means for operating upon a shoe, a pair of stops oppositely movable laterally of the shoe into and out of position over the shoe bottom, and manually operable means arranged first to position said stops over the shoe bottom and then upon further movement to start the operating means.

82. In a machine of the class described, 75 means for operating on a shoe which requires location of the shoe at a predetermined height, means comprising positioning members located on opposite sides of the longitudinal median plane of the shoe and movable toward and from said plane to locate the shoe at said predetermined height, a shoe support, and power operated means for moving the support toward the positioning means.

83. In a machine of the class described, 85 means for operating on a shoe which requires location of the shoe at a predetermined height, means comprising positioning members located on opposite sides of the longitudinal plane of the shoe and movable toward and from said plane to locate the shoe at said predetermined height, a last support, power operated means, and means for locking the support to the power operated means to cause the shoe to be pressed against the positioning means.

84. In a machine of the class described, 90 means for operating on a shoe which requires location of the shoe at a predetermined height, a last support, means having a predetermined positive movement for raising the support, means comprising positioning members located on opposite sides of the longitudinal median plane of the shoe and movable toward and from said plane to engage and locate the shoe at said predetermined height, and means for locking the support to the support raising means to cause the shoe to be positively pressed against the positioning means.

85. In a machine of the class described, 100 the combination of stops arranged to engage opposite sides of the shoe shank adjacent to the heel breast, a shoe support movable to press the shoe against said stops, operating means arranged to remove material from the shoe heel to an extent determined by its relation to said stops, and means for withdrawing the stops from the shoe.

86. In a machine of the class described, 115 means for operating on a shoe bottom, a last support yieldingly held for movement toward and from said operating means, means for limiting movement of the shoe toward said operating means comprising members normally separated to permit passage of the

shoe between them, means for closing the members over the shoe bottom to determine the position which the shoe is caused to assume by said yielding support, and means 5 acting on the support so positioned to effect a predetermined movement of the support toward the bottom engaging members.

87. In a machine of the class described, operating means requiring the shoe to be 10 located in a predetermined position, stops having shoe engaging faces movable in a plane substantially parallel to the shoe bottom from positions laterally beyond the shoe to positions over the shoe bottom at each 15 side thereof to limit movement of the shoe toward the operating means, means for moving the stops over the shoe bottom, and means for supporting the shoe against the stops during the operation of said operating means.

88. In a machine of the class described, operating means requiring the shoe to be located in a predetermined position, stop arms having shoe engaging ends, said arms 25 being movable in a plane substantially perpendicular to the shoe bottom to locate their ends in position to limit movement of the shoe toward the operating means, means for moving the stop arms to shoe engaging position, and means for supporting the shoe 30 against said arms during the operation of said operating means.

89. In a machine of the class described, a cutter having a predetermined movement 35 to treat a shoe heel, a shoe support, a stop having a shoe engaging face to locate the shoe in proper relation to the movement of the cutter, means for raising the support to hold the shoe against the stop, heel tread 40 engaging means arranged to be lifted by the shoe when it is raised by the support, means for engaging the tread face of the forepart of the shoe and co-operating with said heel tread engaging means to locate the shoe in its longitudinal median plane, and power 45 means for applying additional pressure to the heel tread engaging means during operation of the cutter.

90. In a machine of the class described, a cutter having a predetermined movement 50 to treat a shoe heel, a shoe support, a stop having a shoe engaging face to locate the shoe in proper relation to the movement of the cutter, power means for raising the support to hold the shoe against the stop, heel tread 55 engaging means arranged to be lifted by the shoe when it is raised by the support, means for engaging the tread face of the forepart of the shoe and co-operating with said heel tread engaging means to 60 locate the shoe in its longitudinal median plane, and means for applying power pressure to the tread engaging means.

91. In a machine of the class described, means for operating on a shoe bottom, yielding means between which the shoe is held in preliminary position, a stop normally at one side of the shoe out of the way of the shoe heel and movable into position over the shoe bottom in front of the heel or limiting 65 movement of the shoe toward the operating means, and positively power actuated means for effecting final holding pressure of the shoe against the stop.

92. In a machine of the class described, means for operating on a heel attached to a shoe, a last support arranged for movement into and out of operative relation to the operating means and yieldingly upheld toward the operating means, members arranged to engage opposite margins of the shoe sole to limit movement of the shoe toward the operating means, said members being initially out of the way of the shoe in its movement into operative position, means for positioning said members in relation to the shoe bottom to limit movement of the shoe toward the operating means, and means for unyieldingly sustaining the shoe support during operation of the operating means.

In testimony whereof I have signed my name to this specification.

LOUIS A. CASGRAIN.
